UNITED STATES PATENT OFFICE.

JOHN HOWARD SHARP, OF SHAMOKIN, PENNSYLVANIA.

DESIGN FOR A FINGER-RING.

56,388.

Specification for Design.

Patented Oct. 5, 1920.

Application filed May 22, 1920. Serial No. 383,578. Term of patent 14 years.

To all whom it may concern:

Be it known that I, JOHN HOWARD SHARP, a citizen of the United States, residing at Shamokin, in the county of Northumberland and State of Pennsylvania, have invented a new, original, and ornamental Design for a Finger-Ring, of which the following is a specification, reference being had to the accompanying drawings, forming a part thereof.

Figure 1 is a side elevation of the finger ring.

Fig. 2 is an end elevation of the finger ring showing my new design.

I claim:

The ornamental design for a finger ring as shown.

JOHN HOWARD SHARP.
